UNITED STATES PATENT OFFICE.

CONRAD ALBERT SIPE, OF FAIRMONT, WEST VIRGINIA.

BELL-CORD COUPLING.

SPECIFICATION forming part of Letters Patent No. 364,312, dated June 7, 1887.

Application filed March 28, 1887. Serial No. 232,752. (No model.)

To all whom it may concern:

Be it known that I, CONRAD ALBERT SIPE, a citizen of the United States, residing at Fairmont, in the county of Marion and State of West Virginia, have invented a new and useful Improvement in Bell-Cord Couplings, of which the following is a specification.

The invention relates to an improved bell-cord coupling adapted especially for use on railway-cars, the object being to provide a simple and cheap coupling that can be quickly and easily connected and disconnected, and that will not accidentally come apart; and it consists in the construction and arrangement of the metal spring connecting strips at the ends of the sections of cord and the combination of said strips with other parts, as hereinafter described, and embraced in the appended claims.

In the accompanying drawings, Figure 1 represents a perspective view of the device attached to proper supports. Fig. 2 represents a central longitudinal section of the end of a cord having one side or section of the device attached. Fig. 3 represents a perspective view 25 of one of said sections of the device detached. Fig. 4 represents a perspective view of a modification thereof. Fig. 5 is a perspective view of portions of the two ends or coupling-hooks of my improvement.

Referring to the drawings by letter, A A' designate the meeting ends of two similar sections of bell-cord, and C C' the similar halves or sections of the connecting device respectively attached thereto. Each of said halves 35 or sections consists of two similar strips, c c', having their front ends pointed or beveled outwardly and provided with the shoulders c' c' a short distance rearward from said points.

From the shoulder c' of each strip c runs the 40 straight portion or neck c' a short distance rearward. The edge of the strip then inclines rearward and outward, as at c', after which both strips have the same and an equal width to the rear ends. The strips are secured together with their shoulders c' lying upon each 45 other and pointing in opposite directions, a V-shaped notch, D, being formed between the points of the strips, and a space, D', of general rectangular form between the necks c' c'. 50 Each of the said sections or catches is placed within and among the strands of the end of the corresponding bell-cord, and secured by

rivets passing through the cord and strips. The whole is then firmly and evenly wrapped with small cord, E, a piece of soft-rubber tubing, F, passed thereon and bound over all by a suitable cord or other wrapping, the end of the tubing extending nearly to the points of the strips.

To connect two sections of cord provided with the device, the V-shaped notches formed by the points of the latter are placed together at right angles, so that the points of the opposing sections or catches will have passed each other. The two sections are then twisted 65 upon each other, so as to press apart the strips of which each are composed. The hook-shaped ends of the catches will then pass each other, and the shoulders of one section will engage and hold on the shoulders of the opposing section, the elasticity of the strips preventing them from springing apart.

To release the two couplers C and C', they are twisted so as to separate the hooked ends c thereof, when they may be readily drawn asunder by passing between each other.

The rubber tubing, by its contraction on the strips, also aids in preventing them from detaching from each other. It also prevents the points of the strips or catches from injuring 80 the hands of the person connecting the sections of cord, or any parts of the car that they may touch, or breaking the windows in the doors of said cars.

Fig. 4 represents a modification of the device, in which there is substituted for one of the sections of the device a single strip, G, similarly secured to the end of a section of bell-cord, and provided in its outer or front end with a slot, g, which may be engaged by 90 the shoulders c' of the opposing section. The device as described is simple, cheap, and durable, and cannot easily become accidentally disengaged.

Having described my invention, I claim— 95

1. In a bell-cord coupler, the combination, with the bell-cord, of two flexible tubes connected to the ends thereof and spring-couplings mounted within the said tubes and constructed to engage with each other and form 100 a connection inclosed by the tubes, all substantially as described.

2. In a bell-cord coupler, the combination, with the bell-cord, of two rubber cylinders, F,

secured to the ends thereof, and the spring-couplers C and C', arranged in planes at right angles to each other and inclosed within each tube, and which are adapted to engage with each other, as set forth, and when coupled are entirely housed by the said rubber tubes, substantially as described.

3. In a bell-cord coupler, the combination, with the bell-cord, of the two spring-arms 10 cured to the ends of said bell cord in planes at right angles to each other and adapted to couple, as set forth, substantially as described.

4. The combination of the sections of bell-cord A A', the similar sections or catches, C 15 C', composed of the strips c c, each pointed at its end and provided with a shoulder, c', and neck c'', forming between them the engaging

opening D', the points of the strips forming the V-shaped notches D, and means, substantially as described, to connect said sections of 20 cord and catches together.

5. The combination of the sections of cord, the pieces of tubing F, and the catches C C', each composed of the strips c c, pointed, as described, at their ends, and provided with the 25 shoulders c' and necks c'', substantially as specified.

In testimony that I claim the foregoing as my own I have hereto affixed my signature in presence of two witnesses.

CONRAD ALBERT SIPE.
